UNITED STATES PATENT OFFICE.

SAMUEL B. GOFF, OF CAMDEN, NEW JERSEY.

BOTTLE-FILLING MACHINE.

1,140,032.

Specification of Letters Patent. Patented May 18, 1915.

Application filed December 29, 1913. Serial No. 809,263.

To all whom it may concern:

Be it known that I, SAMUEL B. GOFF, a citizen of the United States, residing at Camden, in the county of Camden and State 5 of New Jersey, have invented certain new and useful Improvements in Bottle-Filling Machines, of which the following is a specification.

My invention relates to improvements in 10 bottle filling machines, the object of the invention being to provide improved means for simultaneously filling a plurality of bottles and controlling the opening and closing movements of the outlet valves by the 15 vertical movement of the bottle elevating means.

A further object is to provide an improved construction and arrangement of supply tank having an improved arrangement of valves operated in an improved 20 manner by a bottle elevating means.

A further object is to provide improved elastic supporting and elevating means for the bottles having an improved device for 25 holding the bottles in elevated filling position.

With these and other objects in view, the invention consists in certain novel features of construction and combinations and arrangements of parts as will be more fully 30 hereinafter described and pointed out in the claims.

In the accompanying drawings: Figure 1 is a view in elevation partly in section illustrating my improvements. Fig. 2 is a view in vertical transverse section on the line 2—2 of Fig. 1. Fig. 3 is an enlarged fragmentary view in longitudinal section illustrating one of the valves controlling the outlet of liquid and showing a bottle in position on the outlet nozzle. Fig. 4 is a view in longitudinal section through the center of Fig. 2. Fig. 5 is a view in section on the line 5—5 of Fig. 1 with the crate and its 40 bottles removed. Fig. 6 is a fragmentary view in section on an enlarged scale on the line 6—6 of Fig. 1. Fig. 7 is a view in transverse section on the line 7—7 of Fig. 1.

1 represents a supporting base and 2, 2 50 are standards secured on the base and strengthened by a horizontal bar 3 and by a stationary platform 4, which are connected at their ends to the standards. The standards 2 are provided on their inner faces at 55 their upper ends with channel guides 5 to receive flanges 6 on the ends of a supply

tank 7. These guides have closed rear ends, and their forward ends are closed by pivoted lugs 8 which are adapted to be swung down into position over the outer ends of 60 the flanges 6 and securely hold the tank against movement. The tank 7 is provided in its bottom with a plurality of outlet nozzles 9 conforming in number to the number of bottles 10 to be filled, and having 65 conical sleeves 11 thereon preferably of rubber to enter the open ends of the bottles and form a tight juncture therewith. The inner ends of the outlet nozzles 9 are normally closed by valves 12 which are secured to the lower ends of rods 13 and have weights 14 around the rods to return the valves by gravity to closed position. The rods 13 project through openings 14^a in a cover 15 removably supported on the tank and 70 also project through the top of a housing 16 and also through a plate 17. The extreme upper ends of the rods 13 are screw-threaded for the reception of nuts 18 adjustable on the rods and normally located against 75 the plate 17 so as to permit vertical adjustment of the valves to insure their proper position to close the outlets.

A supply pipe 19 is provided to direct milk into an inlet trough 20 of the tank 7. 85 This pipe 19 has a pivoted valve 21 which is connected by a link 22 with a lever 58. The lever 58 is pivotally supported between its ends, and at its other end is connected to a float 59 in the tank 7 so that this float operates to automatically open and close the valve 21 and maintain a uniform level of liquid in the tank. To prevent any possibility of the cover 15 accidentally moving on the tank, I provide locking rods 23 which 90 are projected through openings 24 in the front and rear walls of the tank, and through sleeves 25 fixed to the bottom of the cover as clearly shown in Figs. 1, 2, and 4.

The plate 17 is secured to a transverse bar 100 26 having its ends bent downwardly as shown at 27 and secured to horizontal bars 28 at the front, and rear of the tank. These bars 28 project through angular guides 29 and have upwardly projecting fingers 30 105 thereon which move through openings 31 in the top of the guides 29 and prevent any possibility of longitudinal movement of the bars 28, yet permit them to move vertically a distance sufficient to open the valves 12. 110 The platform 4 is provided with guides 32 to direct a crate 33 into proper position be-

low the tank 7, and when the crate is in this position, all of its bottles 10 will be located below the nozzles 9. A roller 60 is supported on the platform at the inner ends of the 5 guides 32, and serves as a stop to limit the movement of the crate to guide the latter in position, but when the bottles are filled, the crate may be forced over this roller, and taken off the opposite side of the platform. 10 Crates 33, particularly those designed for carrying milk bottles, are provided with openings 34 in the bottom of the crate below the bottles, and when the crate is properly positioned, these bottles will also be located 15 above openings 35 in the platform 4 in position to be engaged by blocks 36 which are supported by coiled springs 37 secured at their lower ends in sockets 38 on an elevator 39. The elevator 39 is movable in guides 40 20 on standards 2, and the downward movement of the elevator is limited by brackets 41 also secured to the standards as clearly shown in Fig. 1.

At the four corners of the elevator 39, I 25 provide upwardly projecting rods 56 which move through guide openings 57 in platform 4, and are adapted to engage the bars 28 to open the valves as will hereinafter appear. These rods 56, when the platform is in its 30 lowest position, are spaced from the bars 28, so that they do not serve to open the valves until the bottles are in position on the nozzles.

The elevator 39 is supported on the upper 35 end of a plunger 42 which is movable through a guide sleeve 43 on bar 3, and at its lower end is connected to a foot lever 44. The particular connecting device illustrated comprises a bifurcated bracket 45 pivotally 40 connected to the lever 42 by a pin 46 and having on its upper end, a finger 47 projecting into a socket 48 in the lower end of the plunger. The lever 44 is fulcrumed between its ends in a bifurcated bracket 49 on 45 base 1, and is adapted to be locked in position to hold the bottles in elevated filling position by means of a pivoted arm 50. The arm 50 is supported by a transverse rod 51 secured in brackets 52 on standards 2. The 50 arm 50 is free to slide on the rod 51 in one direction, but its movement in the other direction is limited by a fixed collar 53 so that this collar will stop the arm in a proper position over the lever 44. The arm 50 has a sharp end 54 adapted to engage in a notch 55 in the lever and hold the latter in its lowered position to maintain the bottles in position for filling. It will be noted, particularly by reference to Fig. 3, that the rods 13 55 are tubular so that air can pass up through the rods and facilitate the flow of fluid from the tank into the bottles.

The operation is as follows: A crate 33 is placed upon platform 4 in the guides 32, and then the lever 44 is operated to move

plunger 42 and elevator 39 upwardly. This upward movement of the elevator causes the spring-pressed blocks 36 to move the bottles 10 out of the crate 33 and into close engagement with the nozzles 9. After this contact 70 is made, the rods 56 will engage bars 28 and force the said bars 28 and bar 27 with the plate 17 upwardly, thus lifting all of the valves and allowing the liquid in tank 7 to flow into the bottles. If desired, the parts 75 may be locked in this position by moving the arm 50 so as to position its lower end 54 in the notch 55. When the bottles are filled, the lever is allowed to move upwardly, and as the elevator begins its downward movement, the first operation will be to permit the valves to close as the rods 56 will move away from the bars 28 without lowering the bottles. This difference in movement is permitted by reason of the springs 37, and furthermore the springs 37 operate to elastically hold all of the bottles against the nozzles and compensate for any difference in the sizes and shapes of the bottles.

It will be noted that the ends of the 90 nozzles 9 operate as displacement devices inside of the bottles, so that such milk as is contained in the nozzles may flow into the bottles as the latter are lowered, the displacement of the nozzles providing sufficient 95 accommodation for this milk within the nozzles.

Various slight changes might be made in the general form and arrangement of parts 100 described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A bottle filling machine comprising a tank having a plurality of transverse series 110 of nozzles in its bottom, of valves in the tank normally closing the nozzles, rods connected to the valves and projecting through the top of the tank, a single plate connecting all of said rods above the tank, guides on 115 the sides of the tank, horizontal bars vertically movable in said guides, a transverse bar secured between its ends to the plate, and at its ends to said horizontal bars, a vertically movable elevator below the tank, 120 and upwardly projecting rods on the elevator adapted to engage and elevate the horizontal bars, substantially as described.

2. A bottle filling machine, comprising a tank having a plurality of transverse series 125 of nozzles in its bottom, of valves in the tank normally closing the nozzles, rods connected to the valves and projecting through the top of the tank, a single plate connecting all of said rods above the tank, guides 130

on the sides of the tank, horizontal bars vertically movable in said guides, a transverse bar secured between its ends to the plate and at its ends to said horizontal bars, 5 said guides having openings therein, pins on the horizontal bars movable through the guides and preventing longitudinal movement of the horizontal bars, a vertically movable elevator below the tank, and upwardly projecting rods on the elevator adapted to engage the horizontal bars and move them vertically when the elevator is moved upwardly, substantially as described.

3. A bottle filling machine, comprising a tank having a plurality of transverse series 15 of nozzles in its bottom, of valves in the tank normally closing the nozzles, rods connected to the valves and projecting through the top of the tank, a single plate connecting all of 20 said rods above the tank, guides on the sides of the tank, horizontal bars vertically movable in said guides, a transverse bar secured between its ends to the plate and at its ends to said horizontal bars, a vertically movable 25 elevator below the tank, upwardly projecting rods on the elevator adapted to engage the horizontal bars, and a crate supporting platform having openings therethrough for the passage of the rods and having openings 30 therethrough for bottle supporting means on the elevator, substantially as described.

4. A bottle filling machine, comprising a tank having nozzles in its bottom, valves normally closing the nozzles, rods connected 35 to the valves, a plate above the tank connecting all of the rods, a member connected to the plate and projecting from both sides of

the tank, horizontal bars at opposite sides of the tank connected to said member, guides on the sides of the tank limiting the upward movement of the bars, a vertically movable elevator below the tank, and upwardly projecting rods on the elevator normally spaced from the bars and adapted to engage the said bars to elevate all of the 45 valves when the elevator is in bottle filling position, substantially as described.

5. A bottle filling machine, comprising a tank having nozzles in its bottom, valves normally closing the nozzles, rods connected 50 to the valves, a plate above the tank connecting all of the rods, a member connected to the plate and projecting from both sides of the tank connected to said member, guides on the sides of the tank through which the bars project, said guides having openings therein, upwardly projecting fingers on the bars extending through the openings in the guides and holding the bars against longitudinal movement, a vertically movable elevator below the tank, and upwardly projecting rods on the elevator normally spaced from the bars and adapted to engage the 55 said bars to elevate all of the valves when the elevator is in bottle filling position, substantially as described.

In testimony whereof I have signed my name to this specification in the presence of two subscribing witnesses.

SAMUEL B. GOFF.
